UNITED STATES PATENT OFFICE

JAMES E. SPALDING, OF COLLINSVILLE, ILLINOIS

APPARATUS FOR FORMING ICE CUBES

Application filed July 30, 1930. Serial No. 471,644.

This invention relates generally to refrigerators, and more particularly to a device for forming ice cubes from a block of ice.

The advantages of having small cubes of ice for the cooling of beverages and the like is well recognized, such cubes being generally produced by freezing them within a pan or container having a grid-work, within which the cubes are frozen. Another manner in which these cubes have previously been formed is by the cutting of a block of ice by various means, principal among which was a hot electric conductor, into bodies of ice in the shape of a parallelepiped and afterwards severing the parallelepipeds to form cubes of a desirable size. None of these devices, however, is such that it may be applied to an ordinary refrigerator or ice-box and be there operated to form ice cubes.

The object of this invention is, generally stated, to provide a device for forming ice cubes, which is readily adaptable or attachable to an ordinary ice-box.

A further object of this invention is to provide a device of the character described in which the ice by its own weight will form itself into cubes of a desired size.

A more specific object of this invention is to provide a device of the character described in which the penetration of the cube-forming element into the ice block may be controlled.

Another object of this invention is to provide a device for severing knobs of ice from the block upon which they are formed.

Further objects will appear to those skilled in the art when the following description is read in connection with the accompanying drawings; in which:

Figure 1 is a sectional view in front elevation of a refrigerator provided with the cube-forming device of this invention;

Figure 2 is a sectional side view taken along line 2-2 of Figure 1;

Figure 3 is a perspective view of the cube-forming grid-work;

Figure 4 is a view in front elevation of the refrigerator wall and showing one form of guide for directing the movement of a severing member;

Figure 5 is a perspective view of a two

prong ice pick employed in severing the knobs from the block of ice;

Figure 6 is a diagrammatic view of another embodiment of this invention;

Figure 7 is a diagrammatic view of another embodiment of this invention and showing the block of ice with knobs formed thereon;

Figure 8 is a perspective view of an ice saw employed with the embodiments shown in Figures 6 and 7, to sever the knobs of ice from the block; and

Figure 9 is a diagrammatic view, illustrating a method of increasing the pressure on the ice.

In accordance with this invention, the floor of the ice compartment of a refrigerator is provided with a grid-work consisting of intersecting metallic plates upon which a block of ice may rest. In accordance with a well-known principle of physics that portion of the block of ice which contacts with the plates of the grid-work will, by the pressure exerted at this point, lower the freezing point of the ice along the lines of contact, and, accordingly, the medium will return to a liquid state along these lines, permitting the grid-work to penetrate the block of ice, which action is caused entirely by the weight of the ice block upon the grid-work. A plate member may be inserted beneath the block of ice to prevent penetration of the grid-work thereinto, or it may be removed from this position and placed beneath the grid-work to limit the penetration of the grid-work into the block of ice.

Referring now to the drawings, and more particularly to Figures 1-4, 1 designates the walls surrounding an ice compartment of an ordinary refrigerator. Between opposite walls of the refrigerator is supported an ice sustaining floor 2 which is formed of a plurality of perpendicular plates 3, 4, which are vertically disposed and intersected to form recesses of the size in which it is desirable to form ice cubes. It will be observed that the plates 4 are of greater width, that is, of greater vertical extension than the plates 3 which extend at right angles thereto and intersect therewith, and the purpose of this construction will be hereinafter described.

A plate 5, which may be in the nature of

a piece of flat sheet metal of a width which may vary from that slightly in excess of the distance between any two parallel plates to the width of the entire floor, but in the preferred embodiment here illustrated this plate has been shown as wide enough to cover three rows of the cube-forming compartments, is provided. It is thus apparent that when the plate 5 is disposed above the grid-work, as illustrated in Figure 1, the ice block 6 is held in a position above the grid-work 2, and thus penetration of the grid-work into the block is prevented. However, when it is desired to form cubes, the plate 5 is removed from the position illustrated in Figure 1, and inserted beneath the grid-work in the position illustrated in Figure 2; it being supported in this position by the guide member 7 integral with and extending across the front and back of the grid-work 2 adjacent the walls of the refrigerator. Thus when the plate 5 is in the position illustrated in Figure 2, that is, beneath the grid-work 2, the block of ice 6 will be permitted to melt away along the lines 25 in contact with the plates 3 and 4; thus permitting the grid-work to penetrate the block 6 until the knobs formed within the grid-work come into engagement with the plate 5 in its lowermost position, so that further penetration of the grid-work into the ice block is prevented. If now it be desired to remove the cubes which fill one or two rows of the cube-forming compartments, the plate 5 may be disposed beneath that portion of the grid-work from which the cubes have not been removed. Thus the plate will remain in engagement with the ice and prevent further penetration of the block along the area from which the cubes have already been removed, thereby preventing excessive meltage and assuring economy in the operation of the device. When, however, the cubes have been removed from all of the ice-forming compartments, if the plate 5 is left in its lowermost position, illustrated in Figure 2, melting will again take place along the lines in contact with plates 3 and 4, and each of the ice-forming compartments in the grid-work will again be filled until the ice comes into contact with the plate 5.

Beneath the floor 2 of the ice compartment is disposed an inclined tray 8 having at its front portion a trough 9 draining into a spout 10, and it will be apparent that with this arrangement the water produced by melting of the ice is conducted forwardly to the trough 9 and is thence conducted to the desirable outlet or spout 10. The plate member 8 serves the further purpose of collecting the ice cubes when they are severed from the block, as will be hereinafter described, and it is, of course, to be understood that the refrigerator door 11 extends far enough down 65 to permit an individual to extend his or her

hand beneath the floor 2 and gather the ice cubes from the inclined plate 8.

In the embodiment here illustrated, the door 11 is provided with a plurality of apertures 12 which extend therethrough at a level just above the top plates 3, which, it will be recalled, are narrower than the intersecting plates 4 of the grid-work. These apertures are provided in pairs, as clearly illustrated in Figure 4, and it is to be understood that they may be provided in either wall of the refrigerator, if such construction be found preferable to the provision in the door, as here illustrated. A two prong ice pick 13 is illustrated in Figure 5, and the distance between the respective prongs of this ice pick is the same as the distance which occurs between various pairs of apertures 12, so that the pick may be inserted through the apertures 12 in the door 11 and guided in its movement above the plates 3 and between plates 4 to chop the knobs of ice formed within the grid-work from the block to thereby form cubes. It should be understood, however, that the ice pick 13 may be provided with any desirable number of prongs, but that an equal number of apertures must exist in the wall of the refrigerator adjacent each row of cube-forming compartments.

Referring now to Figure 6, an embodiment is shown in which the cubes may be preferably formed of larger dimensions, such as would be desired in commercial use. An ice-box 15 is provided near its bottom portion with a grid-work 16, similar to that illustrated in Figure 3, except that the intersecting plates are of equal height. A slot 17 is provided transversely across the wall of the ice-box 15 adjacent the top of the grid-work 16, whereby a cutting element such as a saw 18, illustrated in Figure 8, may be inserted through the wall of the ice-box and guided in its operation to sever the knobs, formed in the grid-work 16, from the block 19. A doorway 20 is hinged at the bottom of the ice-box 15 to provide access to the compartment beneath the grid-work 16, so that the cubes after being severed from the block 19, may be removed from the box 15.

In Figure 7, an embodiment is illustrated in which a slot 21 for guiding such a saw, such as 18, is provided beneath the grid-work 16 rather than above it, as illustrated in Figure 6, and it will be observed that in this embodiment the grid-work penetrates the ice until the knobs of the desired length are formed below the grid-work 16, at which time the saw 18 may be inserted in the slot 21 to sever the cubes from the knobs which exist in the grid-work. It is pointed out that if the ice-box illustrated in Figure 7, is provided with such a door as 20 in Figure 6, then the guide-way 21 may be formed of a strip of metal extending across the box similar to 7 of Fig-

ures 1 and 2, in the preferred embodiment of this invention.

In Figure 9 is illustrated a means whereby melting of the ice and its formation into cubes may be expedited by the application of greater pressure than would be obtained by the weight of the ice acting alone, as previously described, and this device is particularly applicable to the embodiments illustrated in Figures 6 and 7. In Figure 9 the grid-work 16 is illustrated upon which is resting a block of ice 19. Any suitable lid or supporting structure 22 may be provided to receive a screw 23 which is movable by means of a lever 24 to exert a pressure upon the ice-block 19 through the plates 25 and 26, thus increasing the pressure between the grid work 16 and the block of ice 19, further lowering the freezing point of the ice along the lines in contact with the grid-work and thus causing the ice to melt itself into conformation with the grid-work more rapidly than was possible by employing only the weight of the ice to exert pressure upon the grid-work, as was previously described.

Since it is obvious that many modifications of this invention will occur to those skilled in the art, which will not depart from the spirit of this invention or the scope of the appended claims, it is to be distinctly understood that the embodiments here shown and described shall be construed as merely illustrative and shall not be taken in a limiting sense.

Having thus described the invention, what is claimed is:

1. An ice-box having an ice sustaining floor comprising, a grid-work of intersecting plates, disposed for edgewise contact with a block of ice resting thereupon, and means disposed when in one position to prevent penetration of said plates into said block and when in another position to limit penetration of said plates into said block.

2. An ice-box having an ice sustaining floor comprising, a grid-work of intersecting plates, disposed for edgewise contact with a block of ice resting thereupon, whereby to form ice knobs within said grid-work, and means guided adjacent one edge of the plates for severing said knobs from said block.

3. An ice-box having an ice sustaining floor comprising, a grid-work of intersecting plates, disposed for edgewise contact with a block of ice resting thereupon, whereby to form ice knobs within said grid-work, means guided adjacent one edge of the plates for severing said knobs from said block, and a tray beneath said grid-work for receiving the severed knobs.

4. An ice-box having an ice sustaining floor comprising, a grid-work of intersecting plates, disposed for edgewise contact with a block of ice resting thereupon, the penetrat-

ing edges of plates extending in one direction being extended beyond the penetrating edges of plates extending in the other direction whereby is formed a guideway transversely of the latter plates.

5. An ice-box having an ice sustaining floor comprising, a grid-work of intersecting plates, disposed for edgewise contact with a block of ice resting thereupon, whereby to form ice knobs within said grid-work, means guided adjacent one edge of the plates for severing said knobs from said block, and a member below said grid-work disposed to conduct away drippings from the ice and receive the severed knobs.

6. An ice-box comprising, an ice block sustaining floor having a cube-forming grid-work, and a wall having a guide therein for directing a cutting element to sever the cubes from the block.

7. A device for forming ice cubes, comprising a grid-work for sustaining a block of ice, a cutting device for severing ice cubes formed by said grid-work from the block, and a guide adjacent said grid-work for directing the movement of said cutting device.

8. A device for forming ice cubes comprising, a grid work of intersecting plates having edges arranged to penetrate an ice block, the penetrating edges of plates extending in one direction being vertically offset from the penetrating edges of plates extending in a transverse direction.

9. A device for forming ice cubes comprising, a grid work of intersecting plates having edges arranged to penetrate an ice block, and means arranged below the penetrating edges of some of said plates for guiding a severing device therebetween.

In testimony whereof I affix my signature this 26th day of July, 1930.

JAMES E. SPALDING.
